UNITED STATES PATENT OFFICE

111,100

DESIGN FOR A VEHICLE DIRECTION SIGNAL

Ernest F. Woodworth, Fort Collins, Colo.

Application June 29, 1938, Serial No. 78,146

Term of patent 14 years

To all whom it may concern:

Be it known that I, Ernest F. Woodworth, a citizen of the United States, residing at Fort Collins, in the county of Larimer and State of Colorado, have invented a new, original, and ornamental Design for a Vehicle Direction Signal, of which the following is a specification, reference being had to the accompanying drawing, forming part thereof.

Figure 1 is a view in front elevation of a vehicle direction signal, showing my new design.

Figure 2 is a plan view thereof.

Figure 3 is an end elevational view.

I claim:—

The ornamental design for a vehicle direction signal, as shown.

ERNEST F. WOODWORTH.
